UNITED STATES PATENT OFFICE.

JOSEPH A. FRAUENHEIM AND HARRY ETHERIDGE, OF ZELIENOPLE, PENNSYLVANIA,
ASSIGNORS TO AMERICAN FLEXIBLE BOLT COMPANY, OF PITTSBURGH, PENNSYLVANIA, A CORPORATION OF PENNSYLVANIA.

RAIL-BOND.

1,377,246.

Specification of Letters Patent. Patented May 10, 1921.

Application filed May 31, 1919. Serial No. 300,911.

To all whom it may concern:

Be it known that we, JOSEPH A. FRAUENHEIM and HARRY ETHERIDGE, both citizens of the United States, and both residing at 5 Zelienople, in the county of Butler and State of Pennsylvania, have invented a new and useful Improvement in Rail-Bonds, of which the following is a full, clear, and exact description, reference being had to the 10 accompanying drawing, forming part of this specification in which—

Figure 1 is a side elevation illustrating a rail bond embodying our invention.

Fig. 2 is a sectional plan view of the 15 same.

Fig. 3 is a section on the line III—III of Fig. 2, and

Figs. 4, 5, and 6 are sections taken respectively on the lines IV—IV, V—V and 20 VI—VI of Fig. 1.

Our invention has relation to rail bonds and is designed to provide a durable and efficient bond.

Rail bonds heretofore generally used are 25 formed of copper. If such bonds are made of sufficient length to span the joint and attach to the rails at a proper distance from their joint ends to secure the necessary amount of flexibility, the cost of the bond 30 is not only very large, but the bonds are likely to be cut away and stolen for the value of the copper which they contain. In many cases, therefore, resort is had to the use of a short bond which can be concealed 35 by the joint plates. Such bonds are not of sufficient length to afford the necessary flexibility to take care not only of the expansion and contraction of the rails, but also to the vertical undulations of the same under 40 passing loads. The result is that they soon begin to give away and rapidly deteriorate, making rebonding necessary. At best the bonds heretofore used are very flimsy unsubstantial devices when compared 45 with the track structures to which they are applied.

Our invention provides a rail bond which is designed to be constructed of cheaper metal, such as soft iron, and which can 50 therefore be of a proper length without unduly increasing the cost and danger of the bonds being removed for their value. The use of metal of this character, of course, re-

quires a considerable increase in the cross-section of the bond in order to give it the 55 required conductivity. This, however, enables us to employ a bond which is of strong and serviceable character. In the use of such bond it is necessary to provide special means for increasing the flexibility of the 60 bond. Our invention provides for this by a construction such that the bond will have a maximum flexibility in a substantially horizontal direction at its central portion sufficient to amply take care of the expansion 65 and contraction movement of the rails; while its end portions adjacent to the rails have a maximum flexibility in substantially vertical directions, thereby enabling the bond to take care of the vertical undulations 70 of the rails without injury or deterioration.

Notwithstanding the flexibility of these end portions, the construction is such as to give them sufficient rigidity in a longitudinal direction to properly transmit the end-wise movement of the rails to the flexible 75 central portion of the bond. The construction and operation of such bond is, therefore, distinctly different from that of the usual cable or twisted strand bonds in which 80 an attempt has been made to secure flexibility. In such bonds the character and flexibility is likely to result in an early and progressive failure of the cross-section of the bond at the point where the strains are 85 localized, this deterioration and failure being both with respect to strength and conductivity.

The nature of our invention will be further understood by reference to the accompanying drawing in which we have shown a preferred embodiment thereof and which will now be described, it being premised, however, that the particular form of bond is illustrative only and that the invention 95 may be embodied in various other specific constructions without departing from the spirit and scope of our invention as defined in the appended claims.

In this drawing the numeral 2 designates 100 two rail sections united by the usual joint or fish plates 3. The specific form of bond here illustrated consists of a rod of substantially circular cross-section which is formed by placing together two half round 105 sections 4 and 5 and imparting a twist

thereto. The ends of the bonds are firmly welded to the base flange of the rails at the points 6. The bond may be of any desired length, but preferably sufficient to more than 5 span the joint plates, and to have a distinct outward bow away from the joint, as shown in Fig. 2. In the particular construction shown the two members 4 and 5 forming the bond are twisted by holding their end portions and twisting their central portions 10 through approximately ninety degrees. The bond is so applied that the division, or plane of separation, between the two members 4 and 5 is in a substantially vertical direction; 15 while the plane of division between its end portions adjacent to the rails is substantially horizontal. As will be readily understood, this permits relative movement between the parts and gives the composite 20 bond a maximum degree of flexibility in a horizontal direction at its central portion, and a maximum degree of flexibility at its end portions in a substantially vertical direction. The central portion of the bond is 25 therefore well adapted to take care of the expansion or contraction movements of the rails, while its end portions will take care of the vertical undulations to the rails, all without undue strain upon any portion of 30 the bond. At the same time the bond possesses sufficient rigidity in endwise direction to readily transmit the endwise movements of the rails to its central portion.

As above stated, we preferably form this 35 bond with some relatively cheap metal, soft iron being preferred. This necessarily gives the bond a considerably increased cross-section to that required when copper is employed; but this is more than offset by the 40 relative cheapness of the iron; by the fact that an iron bond of required cross-section is a much more permanent and substantial device; and by the fact that a bond can be made at an increased length without unduly 45 increasing the cost of the bond or the temptation to its being stolen.

While a bond of circular cross-section is preferable from an economical standpoint, it will be understood that this is not essential 50 to our invention but that it may be of any desired shape or cross-section. The twist may also be formed in various ways. Thus, instead of holding the end portions of the bond and twisting its central portion 55 through substantially 90 degrees, the central portion may be held and the ends twisted at substantially 180 degrees to each other. The twisting may also be carried to a considerably greater extent, provided, that 60 the planes of separation between the members are properly disposed at the central and end portions thereof, and that the twists are not too abrupt particularly at the points where maximum flexibility is required.

65 From the foregoing, it will be seen that

our invention provides a rail bond which is constructed with special reference to the nature of the stresses to which such a device is subjected and which is designed to give the required flexibility at the desired points 70 without unduly increasing the flexibility of the bond as a whole. This results in a bond which has a longer life and a higher maintained conductivity than has heretofore been possible. 75

If desired, our improved bonds may be provided with any suitable protective coating, such as a coating of copper.

We claim:

1. A rail bond having its maximum flexibility in a substantially horizontal direction 80 at its central portion, and its maximum flexibility in a substantially vertical direction at its end portions when in bonding position, said flexibility changing gradually 85 throughout the portions of the bond intermediate the central portion and the end portions, substantially as described.

2. A rail bond having a substantially uniform cross-sectional area composed of two 90 separate sections twisted upon each other, with the plane of division between the sections in a substantially vertical direction at its central portion of the bond and in a substantially horizontal direction at its end 95 portions, substantially as described.

3. A rail bond composed of two coöperating semi-circular separate sections twisted upon each other, with the plane of division 100 between the sections in a substantially vertical direction at its central portion of the bond and in a substantially horizontal direction at its end portions, substantially as described.

4. A rail bond comprising two contacting 105 half round sections twisted in a manner to bring the plane of the joint between them in a vertical direction at the center of the bond and in a horizontal direction at its end portions, substantially as described. 110

5. A rail bond composed of a plurality of sections twisted upon each other, the twists at the central portion of the bond being disposed to impart a maximum flexibility in one direction and the twists at the end portions of the bond being disposed to give maximum flexibility in a direction substantially at angles to the first named direction, substantially as described. 115

6. The combination with a rail joint, of 120 a bond extending around the joint and secured to the rails beyond the joint, said bond having its effective bending resisting properties varied gradually throughout different portions of the length thereof to provide maximum flexibility in a horizontal direction at its central portion and maximum flexibility in a vertical direction at its end portions adjacent to the rails, substantially 125 as described. 130

7. The combination with a rail joint, of a bond extending around said joint and having its ends secured to the rails at points beyond the joints, said bond comprising two sections or members twisted upon each other with the plane of division imparting a maximum flexibility of the bond in a horizontal direction at its central portion, and a maximum flexibility at its end portions adjacent 10 to the rails in a vertical direction, substantially as described.

8. The combination with a rail joint, of a bond extending around said joint and having its ends secured to the rails at points 15 beyond the joints, said bond comprising two sections or members twisted upon each other in a manner to impart a maximum flexibility of the bond in a horizontal direction at its central portion, and a maximum flexibility 20 at its end portions adjacent to the rails in a vertical direction, said bond being bowed outwardly around the joint, substantially as described.

9. The combination with a rail joint, of a bond extending around the joint, said bond having its ends welded to the base flange of the rail and its central portion bowed outwardly around said joint, the bond having a maximum flexibility in a generally horizontal direction at its central portion, and a maximum flexibility in a generally vertical direction at its end portions, said flexibility 30 varying gradually between the central portion and each of the end portions, substantially as described.

10. A sectional rail bond having its plane of division disposed to provide maximum flexibility in a substantially horizontal direction at its central portion and its maximum flexibility in a substantially vertical direction at its ends portions.

11. A flexible rail bond comprising a plurality of independent twisted sections co-operating throughout their lengths, said 45 sections being twisted to locate the division plane in a substantially vertical direction adjacent the central portion of the bond, and in substantially horizontal directions adja-

cent the ends portions of the bond, substantially as described.

12. A rail bond composed of a plurality of sections twisted upon each other, the twists at the central portion being disposed with the plane of division imparting a maximum flexibility in one direction, and at the 55 end portions with the plane of division imparting maximum flexibility in directions substantially at right angles to the first named direction, substantially as described.

13. A rail bond composed of separate sections twisted throughout their lengths upon each other, with the plane of division between the sections in a substantially vertical direction at the central portion of the bond and in a substantially horizontal direction 60 at the end portions thereof, substantially as described.

14. A rail bond comprising a plurality of contacting sections gradually twisted throughout its length and having its maximum flexibility in a substantially horizontal direction at its central portion, and its maximum flexibility in a substantially vertical direction at its end portions, when in bonding position, said twisting being arranged to 70 impart a gradually varying resistance intermediate the central portion and each end portion of the bond, substantially as described.

15. A flexible rail bond having its maximum bending resisting properties in a substantially vertical direction at its central portion, and its maximum bending resisting properties in a substantially horizontal direction adjacent its end portions, said bending 80 resisting properties varying gradually intermediate the central portion and the end portions whereby bending strains are uniformly absorbed throughout the major portion of the length of the bond, substantially as described.

In testimony whereof, we have hereunto set our hands.

JOSEPH A. FRAUENHEIM.
H. ETHERIDGE.
